J. Bradbury

Attorney.

UNITED STATES PATENT OFFICE.

FRANCIS A. NOLAN, OF ST. PAUL, MINNESOTA.

RESILIENT SHOE-HEEL.

1,273,175.

Specification of Letters Patent. Patented July 23, 1918.

Original application filed November 26, 1915, Serial No. 63,353. Divided and this application filed October 11, 1916. Serial No. 124,988.

To all whom it may concern:

Be it known that I, FRANCIS A. NOLAN, a citizen of the United States, residing at St. Paul, in the county of Ramsey and State of Minnesota, have invented a new and useful Improvement in Resilient Shoe-Heels, of which the following is a specification, this application being a division of my application for patent filed by me on the 26th day of November, 1915, bearing Serial Number 63,353.

An object of this invention is to provide a resilient shoe heel for permanent attachment to a shoe in such manner as to most effectively prevent the collection of moisture and dirt in cavities or openings which have been formed in the heel. More particularly the novel features of this invention claimed in this application relate to the cushioning means employed and the sealing means for preventing moisture and dirt entering between the heel and the shoe.

A further object is to so construct the heel as to most effectively prevent slipping on the ground. This application is a division of the subject matter set forth in my companion application, Serial Number 63,353, filed on Nov. 26, 1915, for shoe heel. To these ends my invention comprises the features of construction and combination of parts hereinafter described and set forth in the claim.

In the accompanying drawing forming part of this specification, Figure 1 is a side elevation of a detail of a shoe, a portion of the heel thereof being shown in section; Fig. 2 is a top plan view; Fig. 3 is a section taken on the line X—X of Fig. 2; Fig. 4 is another section taken on the line Y—Y of Fig. 2, and Fig. 5 is a top plan of an alternative construction.

In the drawing A indicates a detail of a shoe or boot, it being understood that where the term "shoe" is used throughout the specification and in the claim following, it is intended to be construed as meaning boots, shoes, or any other foot wearing apparel with which resilient heels are adapted for use. The shoe A is shown with a portion of the usual heel 2 secured to the lift in the usual manner. B is my improved resilient heel, which is adapted for permanent attachment to the heel portion 2 of the shoe or, when desired, it may be permanently secured directly

to the lift instead of to the heel portion. My improved resilient heel B may be made out of rubber or other resilient material and is molded or otherwise formed in the shape of the usual heel. The body B of the heel is formed with a cavity 3 in the top side thereof adjacent to the lower surface of the heel portion 2. The rim or margin 4 of the heel surrounding the cavity 3 has embedded in its upper portion a plurality of washers 5, which are suitably spaced apart and through which fastening devices such as nails 6 are driven from the lower side of the resilient heel upwardly into the body of the heel portion 2 of the shoe. Suitable buttresses 6' are formed on the heel B projecting into the cavity 3 to provide material in which the washers 5 are securely embedded to hold the resilient heel securely on the shoe. These washers may be of any suitable form desired, one form being set forth in my companion application for patent above referred to. The fastening means for securing the heel on the shoe may be of any suitable construction, the particular construction not forming an essential part of the invention claimed by this application. The outer margin of the heel is formed with an upwardly projecting lip 7, due to the upper or heel face 8 of the resilient heel being concave. When the resilient heel is secured with its wear surface outermost upon the shoe, the fastening devices hold the heel with its margin compressed tightly against the shoe heel or lift, thereby producing a close joint under compression and causing the heel to compress tightly against the surface upon which it is mounted. The marginal edge 7 surrounds the entire heel and lies in a single plane, thereby assisting in causing the heel to adhere by suction in place.

The body of the resilient heel is formed with columns 9 in the cavity 3, which project upwardly and press tightly against the surface 10, which may be of the heel portion or lift upon which the heel is mounted. The columns 9 when the resilient heel B is secured on the lower face (tread face) 10 of the old heel or pad of the shoe impress themselves against the lower resilient tread face of the heel B and carry a large portion of the superimposed load. The load is thus sustained in distinct spots or zones on the tread or wear surface portion of the re-

silient heel B due to the heel being composed of rubber or other resilient material and these spots or zones become friction spots or zones on the tread surface of the resilient heel B, which reduce and tend to prevent slipping. When desired a single column 11 (see Fig. 5) can be employed instead of a plurality, the same result being accomplished thereby to a different extent.

10 In accordance with the patent statutes, I have described the principles of operation of my invention, together with the apparatus which I now consider to represent the best embodiment thereof, but I desire to have it understood that the construction shown is only illustrative, and that the invention can be carried out by other means and applied to uses other than those above set forth within the scope of the following claim.

15 20 Having described my invention, what I

claim as new and desire to protect by Letters Patent is:—

An elastic-heel having a lower tread surface and an upper side, said upper side being formed with a deep chamber surrounded by a laterally extending continuous surface portion and with an approximately cylindrical column of small diameter and terminating in the plane of the edge of said chamber to remain normally uncompressed, whereby a portion of the load of a person standing upon the heel is immediately carried by the column directly to the tread surface of the heel tending to produce a small sharply defined friction zone on the tread surface.

In testimony whereof I have signed my name to this specification.

FRANCIS A. NOLAN.
